Inventor

J. D. Burdick.

UNITED STATES PATENT OFFICE.

J. D. BURDICK, OF ASHWAY, RHODE ISLAND.

IMPROVED CLAMP FOR CLOTHES-WRINGERS.

Specification forming part of Letters Patent No. 43,286, dated June 28, 1864.

To all whom it may concern:

Be it known that I, J. D. BURDICK, of Ashway, in the county of Washington and State of Rhode Island, have invented a new and useful Improvement in Fastenings for Clothes-Wringing Machines; and I do hereby declare that the following is a full, clear, and exact description of the same, reference being had to the accompanying drawings, making a part of this specification, in which—

Figure 1 is a side view of my invention; Fig. 2, a plan or top view of the same; Fig. 3, a perspective view of an ordinary fastening, drawn for the purpose of showing the difference between it and my invention.

Similar letters of reference indicate corresponding parts in the several figures.

This invention relates to an improvement in fastenings for securing clothes-wringers to wash-tubs or wash-trays.

The invention consists in the combination, with a wringer frame and clamp, of a vertical hinge extending from top to bottom of the clamp-frames, so as to afford complete adjustability without impairing the strength of the attachment.

To enable those skilled in the art to fully understand and construct my invention, I will proceed to describe it.

A represents one side of the metal frame of the "Eureka Clothes-Wringer," previously referred to, and B is the slot or recess in the lower edge of each side A, to form a fork, through the outer prong *a* of which a screw, C, passes, the screw and fork constituting a clamp, by which the machine is secured to the top edge of the tub over which the forks are fitted. These forks in the original machine are fixed or permanent, as shown in Fig. 3, and it frequently occurs that the tub to which the machine is to be attached will not suit the forks in consequence of the curve of the top edge

of the tub being either too large or too small, and great difficulty is experienced in securing the machine firmly to the tub. I obviate this difficulty by having the forks of the frame attached to the other portion by means of a vertical hinge or joint, D, as shown in Figs. 1 and 2, which admits of the forks being adjusted at right angles with the rollers of the machine, as shown in black in Fig. 2, or adjusted in a more or less oblique position with said rollers, as shown in red in the same figure. By this means the forks may be made to suit the curvature of tubs of large and small diameter, and also to suit the side of a rectangular tray or box, which is frequently used for washing purposes.

In Fig. 2 the straight side of a tray or box is shown in black dotted lines, and the curved top of a tub shown in red dotted lines, the fork being shown attached to the latter in red and attached to the former in black.

This improvement will not add materially to the cost of the construction of the machine, while it will greatly augment its value.

I am aware that the clamps of clothes-wringers have before been swiveled to the frame so as to adapt them to tubs of any shape or size; but,

Having thus described my invention, what I claim as new, and desire to secure by Letters Patent, is—

The combination of the wringer-frame A, screw-clamp *a* B C, and hinge D, when the said hinge extends from top to bottom of the clamp-frame, and the various parts are constructed, arranged, and employed in the manner herein shown and described.

J. D. BURDICK.
